Hans Hansen

By his Attorney

Emerson R. Newell

UNITED STATES PATENT OFFICE.

HANS HANSEN, OF MASPETH, NEW YORK, ASSIGNOR TO EASTERN TUBE AND TOOL CO., INC., A CORPORATION OF NEW YORK.

NON-METALLIC FLEXIBLE CONDUIT.

1,376,618.

Specification of Letters Patent.

Patented May 3, 1921.

Application filed July 1, 1919. Serial No. 308,035.

To all whom it may concern:

Be it known that I, HANS HANSEN, a citizen of the United States, residing at 26 Monte Verde avenue, Maspeth, Long Island, 5 New York, have invented certain new and useful Improvements in Non-Metallic Flexible Conduits, of which the following is a clear, full, and exact description.

This invention relates to flexible tubular 10 woven conduits or circular looms such as are commonly employed for carrying electric wires, and a general object of the invention is to improve the construction and to facilitate the manufacture of such looms and particularly to provide a flexible tubular conduit construction which will meet all of the 15 requirements of the fire insurance underwriters, with respect both to crushing tests and to stretching tests.

20 Other objects and important features of the invention will appear from the following description and claims when considered in connection with the accompanying drawings, in which—

25 Figure 1 is a view in side elevation, partly sectioned, of a flexible tubular conduit embodying the present invention;

Fig. 2 illustrates in section one form of improved weft strand in one stage of its 30 manufacture;

Fig. 3 is a section of completed weft strand of the type shown in Fig. 2;

Fig. 4 is a section showing the relative arrangement of the parts of another type of 35 weft strand, and

Fig. 5 is a section through a completed weft strand of the type shown in Fig. 4.

Referring to the drawings, the circular 40 loom shown in Fig. 1 comprises a weft or woof strand 2, helically coiled and interwoven with warp strands 4 of twisted paper and other warp strands 6 of textile fiber, the warp strands 4 and 6 preferably alternating.

To provide for the necessary stiffness in 45 the weft or woof strands 2, these strands are preferably formed of a cord 8 of textile fiber incased within a covering 10 of paper, which may be formed in the manner shown in Fig.

2 by simply wrapping or coiling about the 50 cord 8 a strip of paper and preferably

cementing it in its coiled condition and then preferably flattening the strand thus formed as shown in Fig. 3, or the weft or woof strand may be formed as illustrated in Figs. 4 and 5, in which the incasing covering 12 55 is shown as infolded upon itself and receiving the cord 14 between the folds or between the infolded part and the original strip, the completed strip being preferably molded into the flattened condition shown in Fig. 5, 60 and being preferably cemented in this condition.

From the foregoing description it will be seen that there has been provided a flexible tubular conduit having not only the desired 65 transverse strength to resist crushing strain and the desired resistance to longitudinal stretching by reason of the interwoven warp strands 4 of twisted paper, but also having greater strength than flexible tubular woven 70 conduits heretofore made, by reason of the use of the reinforced weft strands 2. It will also be observed that the reinforced strands 2 are not necessarily restricted to use as weft strands, and that they can also 75 be used as warp strands, thus still further increasing the strength and durability of the construction, and at the same time facilitating its manufacture by reason of the greater strength of these strands and accordingly the greater speed and positiveness with which they can be handled.

What I claim is:

1. In a flexible tubular conduit, a helically coiled weft strand, comprising a cord surrounded by paper, and alternate warp strands of textile fiber and of paper interwoven therewith.

2. In a flexible tubular conduit, a helically coiled flattened weft strand, comprising a cord inclosed within a paper strip infolded upon itself, and alternating warp strands of textile fiber and of paper interwoven with said weft strand.

Signed at New York, New York, this 19th 95 day of June, 1919.

HANS HANSEN.
